UNITED STATES PATENT OFFICE.

IRVING W. BRAY AND FRED E. BRONSON, OF READING, MASSACHUSETTS, ASSIGNEES
TO GLOBE PHONE MANUFACTURING COMPANY, OF READING, MASSACHUSETTS, A
CORPORATION OF MASSACHUSETTS.

TRANSMITTER.

Application filed October 25, 1920. Serial No. 419,430.

To all whom it may concern:

Be it known that we, IRVING W. BRAY and FRED E. BRONSON, citizens of the United States, and residents of Reading, in the 5 county of Middlesex and State of Massachusetts, have invented an Improvement in Transmitters, of which the following description, in connection with the accompanying drawings, is a specification, like letters 10 on the drawings representing like parts.

Our present invention is an improved construction of sound transmitters, specially adapted for use in telephones and hearing aid instruments.

15 The object of the invention is to improve and perfect transmitters and particularly to improve the extremely delicate and sensitive transmitters designed primarily as aids to the hearing of deaf people. Our present 20 invention is directed mainly to the construction of such transmitters, intended to be used with telephones as hearing aids, and we have provided a novel construction which greatly increases the clearness of the sound 25 transmitting as well as producing a desirable amplification of the sound waves, without the objectionable features of prior devices.

In carrying out our invention we prefer 30 to employ a novel type of electrodes, utilizing metallic members therefor, preferably employing electrodes of silver, or silver plate. We have discovered that this feature is of special and peculiar importance in 35 increasing the clearness and distinctness of the sound waves transmitted, while eliminating objectionable noises and outside disturbances. Our improved transmitter has the further advantages of simplicity of construction, cheapness of manufacture, and permanence in its serviceability. The metallic electrodes seem to result in producing a sensitive "silver tone" to the sounds transmitted, and aid very materially in the action 40 of the transmitter as a microphone for hearing aids.

Referring to the drawings, illustrating preferred embodiments of our invention,

Fig. 1 is a cross-sectional view on the line 50 1-1 of Fig. 2, of a transmitter embodying our invention;

Fig. 2 is a plan view shown with the cap and diaphragm partly broken away;

Fig. 3 is a cross-sectional view of the metal ring we employ; 55

Fig. 4 is a side view of the ring shown in Fig. 3;

Fig. 5 is a side and plan view of one of the electrodes;

Fig. 6 is a similar side and plan view of a 60 metallic electrode with varying forms of cells; and

Fig. 7 illustrates a still further modified form of cell in the metallic electrodes.

As shown in the drawings, the transmitter 65 comprises the usual hard rubber or suitable case 1, to which is secured the cap 2 by the interlocking threaded flanged portions as is usual and as clearly shown in Fig. 1. Through the face of the cap 2 are a plurality of openings 7 to permit the free ingress and egress of sound and air waves. Within the case is fitted a frame 4, preferably resting upon shoulders 14 on the case 1, see Fig. 1, which frame has also shoulders 15, to receive and support a metallic ring 3, which ring carries and supports the diaphragm 5.

Attached to the frame 4 centrally thereof and concentrically with the case, is an electrode 6, held by an attaching screw 8 bearing 80 upon an insulating washer 11, said screw fitted into a correspondingly tapped recess in the central part of the frame 4. Preferably, also, we fit an insulating washer 9 under the electrode 6, and between the 85 washer 9 and electrode 6 is applied the connecting lug 10, to which one of the current wires may be secured.

We prefer to form the electrode 6 of silver or metal with a silver plating, and also 90 to recess the face of this electrode, at a plurality of points, as indicated at 20, 20, Figs. 1 and 2. This construction is substantially that as shown in detail in Fig. 5, the central recess 21 being that which receives the 95 washer 11 and head of the retaining screw 8.

This silver or silver plated electrode in the center, increases the amount of current passing through it, by decreasing the resistance of the electrode and also decreasing the 100 contact resistance of the carbon granules in the cell, when agitated under the varying pressure exerted by the diaphragm. It will be noted that the diaphragm 5 is closely covering the recesses 20, which latter are filled 105 with carbon as is customary, and the vibra-

tion of the diaphragm thus produces a microphone effect on the current, and consequently amplifies the sound waves transmitted thereby.

5 We find that varying forms and shapes of the recesses in the electrode are beneficial and in Fig. 6 the electrode 16 is shown provided with a plurality of recesses 22 of substantially conical form. In Fig. 7 we have 10 shown the electrode 26 with the recesses 23 therein of a still different form, which receives the carbon granules and effects a beneficial action upon the current and contact resistance. It will also be appreciated that 15 the ring 3 holds the diaphragm 5 firmly in contact with the carbon granules in the recesses of the electrode, this being effected by the clamping action of the cap 2 thereon in its threaded union with the case 1.

20 It will be appreciated that our improved construction is simple, efficient and economi-

cal and in use we find that the silver or silvered electrode is highly beneficial, while the extreme sensitiveness of the transmitter is preserved and increased, rendering the 25 same suitable for use in hearing aids.

Our invention is further described and defined in the form of claim as follows:

In a transmitter of the kind described, a 30 casing, a frame mounted therein and carrying a silver electrode, insulation between said electrode and frame, a diaphragm in the frame and adapted to be held in contact adjacent the silver surface of said electrode, a clamping ring holding said diaphragm in 35 adjusted position and a transmitter cap screwing onto the casing and forcing the clamping ring onto said diaphragm.

In testimony whereof, we have signed our names to this specification.

IRVING W. BRAY.
FRED E. BRONSON.
